(57) CLAIM

The ornamental design for a taco holder, as shown and described.

DESCRIPTION

FIG. 1 is a top perspective view of a taco holder, showing my new design;

FIG. 2 is a front elevation view, with the rear elevation view being a mirror image thereof;

FIG. 3 is a right-side elevation view, with the left-side elevation view being a mirror image thereof;

FIG. 4 is a top plan view thereof;

FIG. 5 is a bottom plan view thereof; and,

FIG. 6 is a top front perspective view, shown in a condition of use.

The broken lines shown in FIG. 6 depict environmental subject matter that forms no part of the claimed design.

1 Claim, 3 Drawing Sheets
